TUBULAR LAMP SOCKET

John F. Cavanagh, Providence, R. I., assignor to
Guy H. Burt, Providence, R. I.

Application June 27, 1941, Serial No. 399,996

3 Claims. (Cl. 173—328)

This invention relates to a lamp socket, more particularly to lamp sockets for tubular electric lamps, for example fluorescent lamps.

One of the objects of the invention is to provide a lamp socket into which the lamp may be easily and quickly mounted and which will be maintained in mounted position until manually removed therefrom.

Another object of the invention is to provide a socket which is of simple construction and one which may be used at either end of a tubular lamp, making unnecessary the formation of right and left hand sockets.

Another object of the invention is to provide for the positioning of the lamp in the socket by rotation of the lamp about its axis in either direction after it enters the socket.

Another object of the invention is to provide a good firm contact between the contact pins of the lamp and the contacts of the socket.

With these and other objects in view, the invention consists of certain novel features of construction, as will be more fully described, and particularly pointed out in the appended claims.

In the accompanying drawing:

Fig. 1 is an elevation of a lamp mounted in two sockets which are the subject of this invention;

Fig. 2 is a perspective view of one socket;

Fig. 3 is a view of one-half of the body part of the socket with the operating members in position in this half;

Fig. 4 is a central sectional view on line 4—4 of Fig. 3;

Fig. 5 is a view similar to Fig. 3 but illustrating the position assumed by the plunger as the contact pins of the lamp are moved into the socket;

Fig. 6 is a perspective view of the plunger used for maintaining the lamp pins in engagement with the contact members.

In proceeding in accordance with this invention, I form the base of the socket in duplicate halves which are so shaped that they may be molded and, when placed together, will provide suitable channels for the reception and guiding of the parts of the socket. The socket has an end entrance for the pins of the lamp which are received in a slot to be then rotated in either direction by reason of the uniform under-cutting of the walls of the slot on either side of the entrance thereto. I form my contact members with inturned fingers beyond which the pins of the lamp move in entering the slot so that when turned and moved outwardly the pins of the lamp will engage these fingers of the contact

members; and in order to hold the pins in engagement with the fingers, I provide a plunger or presser member for urging the pins in the appropriate direction, which plunger is depressible as the contact pins enter the socket. The curvature of the contact pins and the socket contact members is such as to cause the lamp to maintain a suitable position of rotation.

With reference to the drawing, 10 designates 10 the tubular lamp such, for example, as a fluorescent lamp, which is provided at each end with contact pins 11 and 12. The base of this socket, designated generally 14, is formed of duplicate symmetrical halves 15, 15, each of which is molded of suitable insulating material and provided with channels 16 and 17 for the reception of the working parts of the socket. At the ends of the base a slot 18 is provided which extends inwardly to meet these channels and which 15 opens to the edge 19 of each of the base sections. This slot extends inwardly at substantially right angles to this end edge 19 and is undercut or recessed as at 20 so as to provide portions 21 overhanging this recess. When the two sections 20 15, 15 of the base are in assembled position, this slot extends from an outer face 22 on one side to the outer face 22 on the other side of the base.

The two contact members 23 are of duplicate construction and are positioned in the channel 30 16 to extend substantially lengthwise of the base, extending into the recess provided by the enlarged slot where finger portions 24 of each member extend inwardly toward each other to overhang the recess. These contact members are 35 provided with binding posts 25, accessible from the end of the base opposite the end provided with a slot, such as shown in Figs. 2 and 3, and to which suitable conducting wires may be attached.

40 In the recess 17 a plunger 26 is located which is cut out as at 27 to receive a spring 28 which urges the plunger 26 outwardly into a position to engage the fingers 24. The other end of this spring engages some suitable abutment 29, forming 45 a part of each base section 15. This plunger is guided by the walls of the channel 17 parallel to each face 22 and also guided by the contact members 23 which extend at right angles to these walls.

50 In use, the lamp 10 with its contact pins 11 and 12 at an end will be inserted by movement of one of these pins, such as 11, inwardly through the slot 18, forcing the plunger 26 inwardly against action of a spring 28. After this pin has been inserted to an extent so that the pin

will engage the bottom 30 of this slot, the lamp is rotated about its central axis in either direction but which we may assume here will be counterclockwise, as viewed in Fig. 5. This causes the contact pin 11 to move to the left and the contact pin 12 to move to the right, and upon rotation through 90 degrees, these pins will both engage the end of the plunger to provide a stop and be positioned at right angles to the axis of the slot 18, or at right angles to the position in which they were when inserted into the socket. In this right-angular position, the spacing of the contact pins causes them to engage and slightly spread the contact members 23. The plunger, being relieved of pressure in the position shown in Fig. 5, will follow the contact pins as they are turned to this right angular position so that these pins are beneath the fingers 24, the fingers being curved substantially to form a good fit with the pins in the position shown in Fig. 3. The plunger thus holds the lamp in a position from which it cannot be withdrawn from the socket without initial rotation and with the contact pins of the lamp in firm engagement with the contacts of the socket.

To remove the socket, it is merely necessary to turn the lamp so that the pins can pass through the slot 18 and the spring and plunger will assist in the ejection thereof. It will be apparent that all of the parts except the spring and the contact members will be formed of insulating material.

I claim:

1. A socket for use with a lamp having a pair of spaced contact pins, comprising a base of insulating material with a slot in a face extending to an edge thereof and of a width to receive either of the contact pins and of a depth to receive both of said contact pins, the opposite walls of said slot being provided with undercut recesses, contact members mounted in said recesses and provided with inwardly turned fingers at their ends extending toward said slot to engage said pins when the lamp is rotated from its position of insertion into said slot, and a spring-pressed plunger in said slot for urging the pins into engagement with the finger portions of said contact members.

5 2. A socket for use with a lamp having a pair of spaced contact pins comprising a base of insulating material with a slot in a face extending to an edge thereof and of a width to receive either of the contact pins and of a depth to receive both of said contact pins when inserted in a line coinciding with the axis of the slot, the opposite walls of said slot being provided with undercut recesses to an extent to accommodate the said pins after inserted in the slot and rotated through 90 degrees, contact members mounted in said recesses and provided with inwardly turned fingers at their ends extending toward said slot to engage said pins when the lamp is rotated from its position of insertion into said slot, and a spring-pressed plunger of insulating material in said slot for urging the pins into engagement with the finger portions of the said contact members and compressible by insertion of said pins into the socket.

10 3. A socket for use with a lamp having a pair of spaced contact pins comprising a base of insulating material with a slot in a face extending to an edge thereof and of a width to receive either of the contact pins and of a depth to receive both of said contact pins when inserted in a line coinciding with the axis of the slot, the opposite walls of said slot being provided with undercut recesses to an extent to accommodate the said pins after inserted in the slot and rotated through 90 degrees, said base being formed of duplicate halves with each half provided with contact and plunger channels extending to said slot and together forming locating guides for the contact members, contact members in said channels extending to said recess and provided with inwardly turned fingers at their ends extending toward each other, a plunger of insulating material located in one of said channels and guided by the walls thereof and by said contact members and slidable axially of said slot, and a spring urging said plunger toward said fingers to force the pins into engagement therewith.

JOHN F. CAVANAGH.
